MILES D. JOYNER, OF SAVANNAH, GEORGIA.

ADJUSTABLE GIB FOR CROSS-HEADS.

1,212,140.

Specification of Letters Patent.

Patented Jan. 9, 1917.

Application filed March 21, 1916. Serial No. 85,639.

To all whom it may concern:

Be it known that I, MILES D. JOYNER, a citizen of the United States, residing at Savannah, in the county of Chatham and State 5 of Georgia, have invented a new and useful Adjustable Gib for Cross-Heads, of which the following is a specification.

The present invention relates to an improved form of gib and mounting therefor 10 on a cross head for engagement with the bars of a two-bar guide, and has for an object to simplify and strengthen the gib and reduce the number of flanges and other projecting parts usually employed.

15 Another object of the invention is to provide a peculiar mounting for the gib on the cross head, which mounting admits of the minute adjustment of the gib from time to time, to take up even slight vertical and 20 lateral wear between the guide bar and the gib.

A further object of the invention is to provide an improved locking means, the opposite members or parts of which are detachably carried upon the cross head and upon the gib, respectively, so that the interlocking parts may be easily removed, for 25 continued use with new gibs, and cross heads, or may be removed when they are 30 broken or worn.

Other objects and advantages of the invention will appear from the following description of the present preferred embodiments of the invention, the same being 35 shown in the accompanying drawings, wherein—

Figure 1 is a side elevation of a cross head mounted on a guide, and being constructed according to this invention. Fig. 40 2 is a longitudinal vertical section, taken centrally through the cross head and the parts carried thereby. Fig. 3 is a detail enlarged cross sectional view through the cross head, the gib, and the fastening means for 45 holding the gib on the cross head, the section being taken on the line 3—3 of Fig. 1. Fig. 4 is an inner face view of one of the gibs employed, showing the locking plates in position. Fig. 5 is a transverse section 50 taken through the gib of Fig. 1, and through one of the locking plates. Fig. 6 is a detail enlarged perspective view of one of the locking keys. Fig. 7 is a side elevation of a portion of the cross head, showing a 55 slightly modified form of key secured in position. Fig. 8 is a transverse sectional view, enlarged, taken on the line 8—8 of Fig. 7, showing the modified form of locking key secured in position. Fig. 9 is a longitudinal section through one edge of 60 the cross head, showing a modified form of gib, and a modified form of adjustable locking means therefor. Fig. 10 is a transverse section of the same, taken on the line 10—10 of Fig. 9, and showing a modified form of 65 key secured in position. Fig. 11 is a top plan view of the cross head with the modified form of gib secured thereto by the modified form of locking means. Fig. 12 is a detail perspective view of the modified 70 form of key. Fig. 13 is a detail perspective view of a further modified form of key. Fig. 14 is a sectional view through the locking plate of Fig. 2, and showing in section a still further modified form of locking key. 75

Referring to these drawings, 10 designates a cross head of the usual form, having connection at one end with the piston rod 11, and at its opposite end with the connecting rod 12. Arranged above and below the cross 80 head are the bars 13 of the ordinary two-bar guide. As may be best seen from Fig. 2 of the drawings, the upper and lower faces of the cross head 10 are inclined to converge rearwardly. The cross head 10 85 has, at its opposite sides vertically projecting walls or flanges 14, which extend upwardly and downwardly beyond the upper and lower inclined faces of the cross head. The walls 14 provide therebetween channels 90 or recesses in the upper and lower edges of the cross head. Seated in these channels, and upon the upper and lower faces of the cross head 10, are a pair of gibs 15. Each gib 15 is of a width to snugly fit between the 95 walls 14, and is tapered from end to end to provide an outer face in parallelism with the guide bar 13 and an inner face inclined oppositely to and bearing against the inclined face of the cross head. The longitudinal sliding movement of the gib 15 in the channel of the cross head 10 advances the gib against the guide bar 13, and retains the outer face of the gib at all adjustments 100 in parallelism with the inner side of the 105 guide bar 13.

The gib 15 may be provided, adjacent one end, with a chamber 16 for the reception of a lubricant to be fed through openings 17 to the guide bar 13.

As shown in Figs. 1 to 8 inclusive, each 110 gib 15 has dovetailed, in its inner inclined

face, one or more transversely extending locking plates 18. The locking plates have spaced apart dovetail ribs 19 in their outer faces which extend transversely across the bottom of the gib 15. The plates 18, with their ribs 19, are countersunk and lie flush in the inner inclined face of the gib 15 to admit of the free and uninterrupted longitudinal sliding of the gib 15.

10 As shown, each gib 15 is provided with a pair of these locking plates, and each plate has a long row of the dovetail ribs. It is to be understood that one, two, or more of these plates may be employed, according to 75 the requirements.

15 The cross head 10 has one or more detachable dovetail keys 20 in each of its inclined outer faces, the keys extending transversely through the cross-head 10 opposite the locking plates 18. Each key 20 has on its outer face several dovetail ribs 21 adapted to intermesh with the dovetail ribs 19 of the locking plate. The locking plate 18 is relatively long, and the key 20 is relatively narrow, so that the gib 15 and its locking plate 20 may be shifted longitudinally of the cross head, and transversely of the key 20, into various positions to register the ribs 21 of the key with any desired plurality of the dovetail recesses between the ribs 19 of the locking plate. The gib 15 may thus be adjusted throughout practically the entire length of the locking plate 18. As shown particularly in Fig. 6, this locking key 20 is 25 in the form of a relatively flat plate or base having its opposite longitudinal edges of dovetail form for sliding engagement in a correspondingly shaped transverse slot formed in the outer inclined face of the cross head, and opening through the opposite sides of the same. The inner end of the key 20 is provided with a head 22 extending across the outer face of the base of the key for engagement against the ends of the ribs 19 of the locking plate 18, when the key 20 is driven completely into place. The ribs 21 terminate at their inner ends short of the head 22, such provision being made for the easy manufacture and handling of the key, 30 when making the dovetail ribs 21.

35 The forward or outer end of the key 20 has a longitudinally extending projection 23 in the form of a threaded shank for engagement through the side of the cross head 10, as shown in Fig. 3, to receive thereover a fastening nut 24, which binds a washer 25 against the side of the cross head. The nut 24, as shown in Figs. 1 and 3, has a plurality of diametrically extending slots 26, to receive a cotter pin 27, which passes through an opening formed diametrically through the shank 23. Thus, the nut 24 is locked from turning, and from displacement with respect to the shank 23. The shank 23 projects from the intermediate portion of the 40

key 20 and is preferably of greater diameter than the thickness of the base of the key. For this reason, the base of the key is ribbed or provided with a longitudinal projection 28, in alinement with the shank and the inner face of the key for reinforcing the key and the shank 23. In this instance, the cross head 10 is suitably grooved in the bottom of the dovetail recess to accommodate this bead 28.

75 Each gib 15 is provided at its opposite longitudinal edges with a pair of outwardly extending flanges 29, which form, together with the base of the gib, a channel through which the adjacent guide bar 13 may slide. The outer edges of the flanges 29 and the side walls 14 are flush, as shown in Fig. 3.

80 To take up side wear and prevent lateral play between the cross head 10 and the guide bar 13, the flanges 29 of the gib 15 have their inner faces or walls 30 flared or beveled outwardly, and the edges 31 of the guide bar 13 are converged or beveled inwardly. The edges 31 lie flat against the walls 30, and when the gib 15 is advanced 85 against the guide bar 13, the beveled walls 30 only further advance over the edges 31 and thus take up any wear between the same.

90 Figs. 7 and 8 show a modified form of key 20^a. Here the base is of uniform thickness 95 throughout, and is provided with dovetail ribs 21^a of the same form as disclosed in Fig. 6, but extending throughout the entire length of the base. The key 20^a is inserted from the outer side of the cross head 10, 100 and is provided at its outer end with an upstanding head 22^a, apertured to receive a shank 23^a projecting outwardly from the side of the cross head 10.

105 Two adjusting nuts 24^a are mounted on the threaded shank 23^a at the opposite sides of the head 22^a to hold the latter from inward or outward movement, and to thus retain the key 20^a rigidly in place. A lock nut 27^a may be turned up against the outer 110 adjusting nut 24^a to bind the nuts in position. It is, of course, understood, that the nut 24 and cotter pin 27 of the preferred form may be used for locking the modified form of key in place, and that the preferred form of key may be supplied with this modified form of securing means.

115 In lieu of the locking plates 18 and the dove-tail recesses therein for locking the gib 15 upon the edge of the cross head 10, the modified form of locking means shown in Figs. 9 to 13 may be employed. One or more rows of transverse U-shaped recesses are formed in the inner inclined face of the gib, providing between the recesses transverse ribs 19^a. A locking plate 18^a, of steel, or the like, is embedded or cast in the gib across each row of the recesses to close the open sides thereof. A locking key 20^b, 120 shown in detail in Fig. 12, is in the form of 125

130

one or more bars, rectangular in cross section, carried on the head 22^a. The cross head 10 has, for each row of closed rectangular recesses, one or more transverse

- 5 rectangular slots to receive the bars of the key 20^b, as shown in Fig. 10. The key 20^b is secured in place preferably by the same means shown in Fig. 8, and as above set forth. The locking plates 18 take the place 10 of the dovetail recesses of the preferred form and hold the bars of the key 20^b between the ribs 19^a to hold the gib from outward movement from the cross head 10. The key 20^b may also be held in place by 15 cotter pins 32 engaging through the openings 33 in the free ends of the bars, as shown in Fig. 11. Fig. 13 shows a further modified form of key 20^c composed of a single bar of rectangular form, and having no 20 head. The key 20^c has the openings 33 in its opposite ends to receive the cotter pins 32 to hold the key in place. One or more of these keys 20^c may be employed.

In Fig. 14 is shown a still further modified form of locking key 20^d, with a dovetail intermediate rib 21, and lateral ribs 21^d. The rib 21 meshes between the ribs 19 of the locking plate 18 of Fig. 1. The lateral ribs 21^d are beveled off straight with 30 the outer edges of the base of the key 20^d and are undercut at their inner sides only. The same adjustment may be had between the plate 18 and the key 20^d as in the preferred form.

35 From the above description, it will be readily understood that when it is desired to take up wear between the gib 15 and the adjacent guide bar 13, it is only necessary to withdraw the key 20 from the side of the 40 cross head 10 and release the locking plate 18, and to then slide the gib 15 upon the inclined face of the cross head toward the guide bar 13. When the gib 15 is thus adjusted, the key 20 is again inserted in the 45 cross head 10, the gib 15 being moved longitudinally until the dovetail ribs 19 and 21 intermesh, and the key is then driven into place and secured, such as by the nut 24 and cotter pin 27.

50 The key 20 is of dovetail formation, and the locking plate 18 is of dovetail formation, so that all of these parts are interlocked and the gib 15 is held not only from longitudinal movement within the channel 55 at the outer edge of the cross head 10, but is also held close to the cross head, and from any outward movement toward the guide bar 13. For the purpose of insuring the withstanding of wear upon the gib 15, 60 it is preferable to form the gib of Hunt-speller's white-gray iron, which is found to withstand the hard usage and wear to which gibs are subjected.

The locking plates 18, which are dove- 65 tailed into the gibs 15, may be easily re-

moved from the gibs by driving the plates laterally therefrom. Should the locking plates become loose, the side walls 14 of the cross head 10 provide stops to prevent the lateral movement of the locking plates, and thus hold all of the parts from any lateral or longitudinal displacement. This interlocking of the parts from movement in all directions is controlled by the fastening device, which is positioned upon the outer 70 end of the key, so that this fastening device of the key must first be released to admit the withdrawal of the key, the gib must then be withdrawn, and finally the locking plates 75 may be taken out of the inner face of the gib. The locking keys 20 are so placed in the cross head 10 that they are capable of withstanding considerable pressure, and do not have to be made unnecessarily large or cumbersome. Consequently, relatively 80 small recesses or openings may be provided 85 in the cross head for accommodating these keys.

Figs. 9, 10 and 11 show a modified form of gib 15^a which is split longitudinally into two sections or halves, each section carrying one of the flanges 29^a. The inner walls 30^a of the flanges 29^a are straight and parallel to each other. The outer walls 34 of the flanges 29^a are converged or beveled longitudinally from one end of the gib 15^a to the other end thereof. The inner walls 35 of the flanges 14 are planed or beveled off to flare from one end of the cross head 10 to the other end thereof. The walls 34 and 35 are oppositely beveled to lie flat against 90 each other throughout the entire lengths of their overlapping portions.

The inner edges of the sections of the gib 15^a are reduced in thickness and overlapped. One section is recessed in its upper face to reduce the edge thereof and provide a shoulder 36. The opposite section is reduced in its lower face to reduce the inner edge thereof and provide a shoulder 37. 100 The shoulders 36 and 37 receive the inner edges of the opposite sections thereagainst 110 when the sections are fully collapsed.

The guide bar 13 has vertical parallel edge walls 31^a to receive thereagainst the 115 straight inner walls 30^a of the flanges 29 of the gib. Longitudinal adjustment of the gib 15^a moves the beveled walls 34 and 35 relatively to each other and advance the gib sections toward each other against the opposite edges 31^a of the guide bar 13, and also moves the gib 15^a as a whole outwardly 120 against the inner face of the guide bar. This adjustment takes up lateral and vertical wear between the guide bar 13 and the 125 gib 15^a.

The keys 20^b and 20^c may be of any other desired cross sectional configuration than rectangular as shown, and the recesses or channels in the cross head 10 and gib 15 130

are preferably correspondingly formed to provide a close fit for the keys and to prevent any loose play of the gib on the cross head.

5 All of the forms of keys 20 shown and above described are set forth as extending transversely through the cross head 10 and gib 15. It is to be understood that these keys may extend at any desired angle or 10 angles across or transversely of the cross head and gib and not necessarily at right angles to the longitudinal axis of the cross head.

It is, of course, understood that various 15 changes and modifications may be made in the design and formation of the several parts of the above described embodiment of the invention, without departing from the spirit of the latter, and being restricted 20 only by the scope of the following claims.

What is claimed is:—

1. In a device as specified, a guide bar, a cross head, a gib adjustable on the cross head for advancement toward said guide bar 25 to take up wear between the same and the inner face of the guide bar, and means for adjusting the gib against the lateral edges of the guide bar to take up the lateral wear therebetween.

30 2. In a device as specified, a guide bar, a cross head, a gib between the cross head and the guide bar to take up the wear of the guide bar, said cross head and said gib having oppositely inclined contacting faces 35 whereby the longitudinal movement of the gib on the cross head advances the gib outwardly toward the guide bar to take up wear upon the inner face thereof, and means on the gib to advance the same against the 40 lateral edges of the guide bar to take up lateral wear therebetween.

3. In a device as specified, a guide bar, a cross head, a gib mounted for longitudinal movement in the cross head and adapted for 45 advancement thereby toward the guide bar, a locking key carried by the cross head and engaging said gib to hold the same from longitudinal movement on the cross head and from outward movement toward the 50 guide bar, and means for advancing the gib against the lateral edges of the guide bar upon said longitudinal movement of the gib.

4. In a device as specified, a cross head having projecting side walls and a longitudinally inclined face between the side walls, a longitudinally tapered gib arranged 55 between the side walls on said inclined face and provided at its inner side with a longitudinal row of interlocking recesses, a transverse key mounted in the cross head and having ribs engaging in said recesses of the gib to lock the latter from longitudinal and outward displacement with respect to the cross head, and means for detachably securing 60 the key in the cross head.

5. In a device as specified, a cross head having projecting walls and an inclined face between the walls, a tapering gib arranged between the walls on the inclined face and adapted for movement thereover to advance 70 the gib outwardly from the cross head, and a locking key secured in the cross head, said gib having recesses therein for interlocking engagement with said key to hold the gib from outward displacement from between 75 said walls and also from adjustable movement over the inclined face.

6. The combination with a cross head having projecting side walls, of a tapered longitudinal gib arranged between the said walls, and provided at its inner face with a longitudinal row of dove-tail ribs, a transverse key dove-tailed in the cross head, and having a plurality of dove-tail ribs interlocking with said row of ribs at any point 85 throughout the length of the row to secure the gib to the cross head in the desired longitudinally adjusted position, a head on the inner end of said key for engagement with the ribs for limiting the inward movement 90 of the key, and securing means on the opposite end of the key for holding the same in place when adjusted.

7. The combination with a cross head having projecting side walls, of a tapered longitudinal gib arranged between the side walls, a detachable locking plate secured in the inner face of said gib, a transverse key secured in the cross head, and adapted to interlock with said locking plate for holding the gib 95 from longitudinal movement upon the cross head.

8. The combination with a cross head having projecting side walls, and a tapered longitudinal gib arranged between the side walls, of a locking plate dovetailed into the inner face of said gib and having inwardly extending dovetail ribs, and a dovetail key detachably secured in the cross head, and having a plurality of outwardly extending dovetail ribs adapted to interlock with the dovetail ribs of said locking plate.

9. The combination with a cross head having projecting side walls, of a tapered longitudinal gib arranged between the said walls, a relatively long locking plate dovetailed into the inner face of said gib, and having inwardly extending dovetail ribs counter-sunk in the inner face of the gib between said walls, and a relatively narrow key dovetailed into the cross head, and having dovetail ribs outstanding from the cross head for interlocking engagement between the ribs of said locking plate, a head on said key to limit the insertion thereof 115 through the cross head, and means on the key for securing the same in interlocking engagement with the locking plate.

10. The combination with a cross head having projecting side walls, of a tapered 120

longitudinal gib arranged between the side walls, a plate dovetailed into the inner face of the gib, and a key secured transversely through the cross head, and having outstanding ribs adapted to interlock with the ribs on said locking plate, said key being relatively narrow, whereby to engage with any of said ribs in the locking plate for holding the gib in various longitudinally 10 adjusted positions.

11. The combination with a cross head having projecting side walls, of a tapered longitudinal gib arranged between the side walls, locking means extending inwardly 15 from the gib, a key extending transversely through the cross head for engagement with said locking means, and having an outstanding threaded shank for engagement through the side of the cross head, a nut turned up 20 upon said shank and against the cross head to hold the key in place, and having a plurality of radial slots in its outer end, and a cotter pin secured in said slots transversely through said shank for locking the nut 25 thereon and against the cross head.

12. The combination with a cross head having projecting side walls, of a tapered longitudinal gib arranged between the side walls, a row of depending dovetail ribs extending transversely across the inner face of 30 the gib, a locking key dovetailed into the cross head, and extending from side to side thereof, a plurality of outwardly extending dovetail ribs on said key adapted to interlock with the ribs on said locking plate by 35 the transverse sliding movement of the key, a head extending across the inner end of the key at the inner ends of the ribs on the key, and adapted to abut the inner ends of said 40 ribs on the locking plate to limit the sliding movement of the key in the cross head, an intermediate longitudinal enlargement on the under side of said key for reinforcing the same, a threaded projection extending 45 outwardly from the forward end of the key and adapted to pass through the side of the cross head, a nut carried on said projection to hold the key in place, and means for securing the nut from accidental dislodgement 50 from the threaded projection.

13. The combination with a cross head having projecting side walls, of a tapered longitudinal gib arranged between the side walls, locking ribs carried upon the gib within the inner face thereof, a transverse 55 key slidable in the cross head, and having projecting ribs adapted to interlock with the ribs of said gib, a head on said key to limit the insertion thereof into the cross head, a projection on said key, a nut engaging said 60 projection to secure the key in the cross head, and means for locking said key from detachment.

14. In a device as specified, a cross head having projecting side walls with transversely registering openings formed in the bases thereof, a key composed of a bar extending through said openings in the side walls and extending across the space between said walls, a gib mounted for longitudinal adjustment between the side walls and having a row of openings in the base thereof adapted to register one at a time with the openings in said side walls, said key being adapted for engagement at its intermediate portion through the openings in said gib whereby to lock the same from longitudinal movement between the side walls and from outward displacement from the cross head.

15. In a device as specified, a cross head having projecting side walls and an inclined face therebetween, a gib with an inner inclined face seated between said side walls and having outwardly flaring flanges, a guide 85 bar having inwardly tapering lateral edges adapted to seat snugly between said outwardly flaring flanges, and means for securing the gib in adjusted position longitudinally upon said inclined face of the cross 90 head to advance the gib toward the guide bar and take up wear at the inner face and at the lateral edges of the guide bar.

In testimony, that I claim the foregoing as my own, I have hereto affixed my signature in the presence of two witnesses.

MILES D. JOYNER.
